TRANSMISSION SYSTEM FOR STATISTICAL DATA

James W. Bryce, Glen Ridge, N. J., assignor to International Business Machines Corporation, New York, N. Y., a corporation of New York

Application October 19, 1938, Serial No. 235,821

8 Claims. (Cl. 178—2)

This invention relates to transmission systems for statistical data and more particularly to systems of the type which provide verifying means at a primary station for data recorded at a remote secondary station. One form of such a system is disclosed herein, another form being shown in my copending application Serial No. 235,819, and still another form being shown in my copending application Serial No. 235,820.

5 Transmission systems with check-back means for the data received at a secondary station are old, a considerable number of different methods being known at the present time, but in a great majority of these systems it is possible for the 10 data received at the secondary station to differ from the data actually recorded at the latter station so that, even though the system checks as to the data received, the recorded data may be in error and this error remain unnoticed.

15 It is therefore an object of the present invention to provide data transmitting means at a first station for effecting the reception and duplication of said data at a second station and novel comparing means under direct control of the 20 duplicate data for comparing such data with the original data transmitted at the first station. Thus, by having a comparing means controlled directly from the recorded data a greater assurance of the accuracy of the system is provided.

25 According to the present invention, a contact control key at a station A is operated to send out a series of impulses which cause a record card to be fed into a punching position at a station B, located at a distant point from station A. Then, upon depression of a character key, printing of the corresponding character is effected at station A, and at the same time a series of impulses are sent to station B to 30 cause the energization of a chain of relays there to a predetermined extent dependent upon the character transmitted. These relays control the operation of means for printing and punching the character at station B. The character is 35 punched in a column of a record card. Other characters are transmitted in a similar manner and are punched in different columns of the record card which are successively presented at the punching station. After the card 40 is completely punched in its data-receiving columns, it is fed past an analyzing station where it is analyzed column for column and multiple impulses representing the characters punched in each of the columns are retransmitted to station A. At station A, this data is received and

printed to provide a visual check against the previously printed data at station A. If there is an agreement, a new record card feed and carriage return is initiated. If there is no agreement, an adjusting key at station A is depressed 5 to adjust station B and also visually to indicate at that station the failure of the re-transmitted data to verify. At station B the newly punched record card is removed and, after station A has adjusted B, station B adjusts A. Operations are 10 then resumed as before. The importance of having an accurate check-back on the transmitted data as described above, especially in statistical work which deals primarily with numerical values, is well realized by those familiar with the 15 art.

Further objects of the instant invention reside in any novel feature of construction or operation or novel combination of parts present in the embodiment of the invention described and 20 shown in the accompanying drawings whether within or without the scope of the appended claims and irrespective of other specific statements as to the scope of the invention contained herein.

25 In the drawings:

Figs. 1 and 1a are representative circuit diagrams of the transmitter and receiver respectively at station A.

Fig. 1b is a timing chart for the circuit diagram shown in Fig. 1.

Figs. 2 and 2a are representative circuit diagrams of the receiver and transmitter respectively at station B.

Fig. 2b is a timing chart of the circuit diagram shown in Fig. 2a.

Fig. 3 is a plan view of a portion of the transmitted keyboard.

Fig. 4 is a sectional view taken at 4—4 of Fig. 3.

Fig. 5 is a sectional view taken at 5—5 of Fig. 3, showing a transmitting key and the various operating mechanism associated therewith.

Fig. 6 is a view of the dash pot control mechanism which is applied to certain relay contacts 45 in the various circuits of the system.

Fig. 6a is a detail plan view of the mechanism associated with the dash pot.

Fig. 7 is a vertical section taken through the analyzing, punching and card feeding mechanism 50 of the punching machine.

A preferred embodiment of the invention will now be described with reference to the accompanying drawings. At station A a special keyboard is provided as shown in Figs. 3, 4 and 5. 55

Seven keys are shown as representative, three of them being allotted to numerical characters and the remaining four being provided for various control operations such as space control, card feed, verifying, and adjusting. If more than three different numerals are to be transmitted more numeral keys are added, but the four control keys are sufficient regardless of an increase in the numeral keys. Depression of any of the keys causes the operation of a special set of contacts associated therewith so as to initiate a corresponding impulse or series of impulses. If a numeral key is depressed, it also causes printing of the numeral by energizing a print solenoid associated therewith, all of which will be described in detail hereinafter. The mechanism illustrated in Fig. 5 in association with the adjust key 17 is similar to that for the other keys. It is seen that the depression of key 17 causes an insulated conducting portion 17a to bridge the contact springs 17b. A notched projection 17c at the same time cams latch bar 19 to the right and then allows it to return to the left again under spring action so that the left extremity of bar 19 is positioned above the latch point on projection 17c to hold the key down. Then at a later time, as will be described later, solenoid 18 becomes energized momentarily to move the latch bar 19 to the right away from projection 17c, thus releasing the key 17 and allowing it to raise to its normal position under the urging of its return spring 17d. It will be noted that only one key may be depressed at a time due to the presence of locks 9 (Fig. 4). When a key is down it maintains the locks adjacent thereto spread apart so that the combined clearance of the locks 9 is taken up and no other key may be moved down between them. This structure is elementary and similar to that used in key-operated punches to prevent the operation of more than one key at a time so that no further description is believed necessary.

A transmitter commutator 20 (Fig. 1) and a rotatable arm 21 are also located at station A, arm 21 being maintained continuously rotating in a clockwise manner at uniform speed by any suitable means such as an electric motor (not shown). The speed at which this arm is to rotate is determined by two factors; namely, the desired speed of transmission of the impulse and the speed of functioning of the receiver mechanism at station B. An arm 21 traverses the various transmitting segments of the commutator 20, a plurality of circuits are successively closed depending upon which of the keys 11 to 17 was operated to effect the transmission of a predetermined number of impulses from the transmitting device 43. The circuits will be described in detail later.

The mechanism actuated at the receiver of station B by the incoming impulses comprises a chain system of multiple contact relays R1 to R7 (Fig. 2) which control the selective energization of a plurality of print solenoids, such as the one designated 62 for example. Solenoid 62, upon becoming energized, pulls its armature 62a and the key lever connected thereto down so as to operate a printing mechanism which is grammatically represented by a platen 57, a hammer 57a, and suitable linkage 57b connected between the hammer and the key lever. Motion transmitted through the linkage 57b causes the hammer to be moved toward the left to strike the platen. The leftward movement of the ham-

mer closes a contact 62b to energize a punch solenoid 72 by a circuit to be described later. Punching mechanism of any convenient type such as shown in the U. S. Patent No. 1,772,186 to F. L. Lee et al., for example, may be employed. Printing and punching under solenoid control are old in the art, and therefore the representation of the printing and punching means illustrated in Fig. 2 and Fig. 7 respectively are believed sufficient.

After the record card has been completely punched it is re-fed into the punch and is permitted to move out again column by column during which movement it is analyzed for the character perforation therein. The analyzing station is located just beyond the punch die and comprises contact balls 22 (Fig. 7) mounted in an insulating support and spring-pressed towards the card C. Above the card there is a contact block 23. It is understood that, when a perforation passes over one of the balls 22, that ball is urged upwardly by its spring to establish contact with the contact block 23.

In order that the re-feeding of the card for analyzing purposes may be effected properly, it becomes necessary to suppress the feeding of a new card into the punch at this time. The mechanism shown in Fig. 8 is therefore provided. The magnet 77 becomes energized when the card has reached the last column. After the last column is analyzed, the feed stroke occurs as will be explained later but lever 78 cams down the card feed knife edge 79 so that it fails to feed a new card C. After the feed stroke, magnet 77 becomes deenergized and the card feed knife 79 raises to its normal operating position.

A device for retransmitting multiple impulses to station A to represent the character perforations in the record card in turn as they are analyzed at station B comprises a commutator 24 with a rotating arm 25 and a transmitter 125. A chain system of relays forms a receiving means at station A similar to that already described for the station B receiver. Arm 25 is rotated in a uniform manner by means similar to that for arm 21 but not necessarily at the same speed.

Although the commutators at stations A and B do not run in synchronism, there is a certain time controlled relationship between the receiving portion of each of those stations and the transmitting portion of the other. This comprises a control relay 55 at the receiver of each station having dash pot mechanism generally designated 54 (Fig. 6) associated therewith to control the time of operation of a plurality of sets of contact including those designated 55b, 55c, 55d, and 55e. Relay coil 55, upon becoming energized attracts the armature 5 so that a cylinder 5a attached to the right extremity of the armature is moved down forcing air out through an opening 7 in the dash pot 54. It is seen that the speed of closing of contacts 55b, 55c, 55d, and 55e are dependent upon the size of the opening 7 which is adjustable in a manner to be explained presently. When the relay coil 55 is deenergized, the outside air rushes in through the opening 8 and the armature is allowed to restore quickly under spring action and return the above contacts to their normal position.

The size of the opening 7 is manually adjustable by turning knob 6' which is fixed to a threaded shaft 6. Automatic means for rotating the shaft 6 in either direction is also provided so as to speed up or slow down the closing

of the contacts under control of the dash pot mechanism. A train of gears, generally designated 4, connects the shaft 6 for operation by a differential device 66 actuated by a pair of pawls 91, 92 and ratchets 66a, 66b. The shaft 6 forms a frictional mounting for one of the gears of the above train. The ratchets may be locked or released according to the position of a pair of cooperating detents 2 and 3. The detents are normally in the position shown in the drawings and are mounted on a common shaft 1. A solenoid X controls the engagement and disengagement of the detents. When detent 2 is disengaged from ratchet 66a, detent 3 is engaged in ratchet 66b. A magnet 135, when energized, causes the pawl 91 to feed ratchet 66b clockwise one tooth. A magnet 136 cooperates with pawl 92 to feed ratchet 66a counterclockwise one tooth. The manner in which these magnets are energized will be better understood later from the description of the circuits of the system. It is sufficient for the present to state that the stepping of ratchet 66b in a clockwise direction causes the threaded shaft 6 to back up by motion transmitted thereto through the gear train 4 and allow an increase in the size of opening 7. On the other hand, the counterclockwise movement of ratchet 66a causes motion to be transmitted through the gear train 30 4 to turn shaft 6 clockwise thereby decreasing the size of the opening 7. Thus, ratchet 66b is operated in the direction indicated by the arrow to speed up dash pot action and ratchet 66a is operated to slow down this action. The solenoid X is located in series with magnet 136 and is energized when the latter is energized so as to release the ratchet 66a. Ratchet 66b is normally free of detent 3 so that solenoid X need not be operated upon the operation of magnet 135. The purpose of the dash pot control mechanism and the automatic adjustment therefor will be explained in connection with the explanation of the circuits and operation of the system which now follows.

At the start it is assumed that the printing means comprising two typewriters at station A and one at station B have paper inserted therein and that the punch at station B has a pack of fresh record cards in its hopper, and that the two stations are in adjustment which is described later. It is first necessary to feed a card from the hopper between the die and stripper of the punch to a punching position. This is accomplished by transmission of a predetermined number of impulses from station A to station B. These impulses cause the energization of a selected control magnet of the chain relay system already described which in turn causes the punch clutch magnet to be energized in a manner to be described presently. A key 15 (Fig. 1), referred to as the card feed key, is depressed (see Fig. 5 and Fig. 1) to initiate the above operation.

The depression of the card feed key 15 causes conducting portion 15a to bridge contact springs 15b and complete a circuit to connect relay coil 35 directly across the line. Relay 29 also becomes energized by a circuit from right hand side of the line 27, wire 28, contacts 35a now closed, relay coil 29, to left hand side of the line 26. Relay 29, when energized, closes its contacts 29a which in turn complete a circuit to energize clutch magnet 40 as follows: right hand side of the line 27, contacts 29a now closed, clutch magnet 40, to left hand side of the

line 26. The energization of magnet 40 causes the cam associated with contacts CC-3 to be clutched in for rotation with the same shaft which carries arm 21. Cam CC-3 therefore now rotates in synchronism with the arm 21 from the "D" position onward. Near the end of the next cycle, the cam causes the closure of its contacts CC-3 for a purpose which will be explained later. It might be well to mention here that the depression of any of the keys 11 to 17 causes the clutching in of the CC-3 cam to the commutator shaft and the energization of relay coil 29.

The energization of relay 35 upon depression of the card feed key 15 causes the closing of contacts 35a and c-g. A circuit is completed through contacts 35a at the time arm 21 contacts segment 20a of the commutator 20 in the following manner: from line 27, wire 28 to contacts 35a now closed, relay coil 30, contacts 39b, commutator segment 20a, arm 21, to line 26. Relay coil 30, upon becoming energized by the above circuit, closes its contacts 30a to cause the energization of relay coil 38 from line 27, contacts 30a, relay coil 38, to line 26. The holding circuit for relay 38 is through contacts 38a now closed and cam contacts CC-1. As previously mentioned, the CC cams are driven at the same speed as arm 21, and when the arm 21 is at line D of commutator 20, the CC cams are in the well-known "D" position as illustrated in the timing diagram (Fig. 1b). Relay 38 is provided with contacts 38b which are located in series with the transmitter 43 and are normally open. Thus, it is seen that transmission may be effected only when the energization of relay coils 30 and 38 has occurred previous to the passage of arm 21 over the various transmitting segments of the commutator 20.

With relay 38 energized, a series of impulses 40 may now be transmitted. The transmitting circuit is from line 27 through resistance 41, contacts 38b now closed, wire 42, contacts 35g now closed, relay coil 45, segment spot 20b, arm 21, to line 26. The flow of current through resistance 41 causes a potential drop across it which is impressed upon the input of the transmitter 43 to cause an impulse to be sent out from station A to station B. Relay 45, upon being energized by the previously traced circuit, closes its contacts 45a to energize relay coil 44 from line 27, through relay contacts 45a, through relay coil 44, to line 26. Relay coil 44 is then held energized through its contacts 44a and cam contacts CC-2 until the end of the transmitting period (see timing diagram, Fig. 1b). As the rotating arm 21 successively contacts the segment spots 20c, 20d, 20e, and 20f, additional impulses are sent out from transmitter 43. In this case, that is, where key 15 is depressed, the contacts 35c through 35g cause transmission of impulses, five in number. Assuming the key 15 has been released by the operator, it is still held in a down position by latch 19 in a manner already described for key 17.

Following the transmitting portion of the cycle, a circuit is completed to energize relay coil 39 by means of the arm 21 from line 26, through arm 21, through segment spot 20n, through contacts 44b now closed, relay coil 39, to the other side of the line 21. Relay coil 39 is held energized through its contacts 39a and relay contacts 29b now closed. The energization of relay coil 39 by the above circuit opens its contacts 39b and prevents energization of the relay coil 30.

should the key 15 remain depressed for another machine cycle. This effectively prevents transmission of a repeated series of impulses for the same depression of the key. Key 15 is released 5 near the end of the cycle when cam contacts CC-3 close to energize relay 18, which shifts latch 19 (Fig. 5) to permit key 15 to move upward under spring action in the same manner as illustrated for key 17. If the operator, however, has not yet released key 15, the shifting of latch 10 19 has no effect and magnet 40 remains energized due to continued closure of relay contacts 29a. Once the operator removes pressure from the key, however, the next shifting of latch 15 19 will release key 15 thereby deenergizing relay coil 28 and consequently relay coil 39. Relay contacts 39b then are allowed to close once more and, upon the next key depression, a new series of impulses may be transmitted.

20 The five impulses transmitted in the manner just described are received at station B and effect a card feed there as follows: Upon reception of each impulse at station B (Fig. 2) the receiver 50 is actuated accordingly and causes the energization 25 of relay coil 52 for each impulse. Coil 52 closes its contacts 52a upon each energization. The first impulse completes a circuit from line 46, relay contacts 52a now closed, through center and upper relay contacts 51a, R1b, R2b, etc., 30 through R1b, wire 49, relay coil 51, and back to the other side of the line 47. Relay coil 51 then shifts its "make before break contacts" 51a, that is, the center and lower contacts make before the center and upper break. Coil 51 thus remains 35 energized for the duration of the first impulse through relay coil 52. Contacts 51b close and cause the energization of relay coil R1 from the left-hand side of line 46, through contacts 53a, contacts 51b, contacts R1a, relay coil R1, to line 40 47. Relay coil R1 is maintained energized through contacts R2d, the holding circuit being from line 47, relay coil R1, contacts R1a, relay contacts R2d, contacts 53a, to line 46. The contacts R1a are also of the "make before break" 45 type. Relay contacts 51c also close to cause the energization of relay coils 55 and 55' by completing a circuit from line 47, relay coils 55 and 55' in parallel, contacts 51c now closed, to line 46. The holding circuit for these coils is through contacts 55'a, 60, 61, 53b, and 63a.

55 A plurality of contacts are operated under the control of relay coils 55 and 55'. Those operated by coil 55, including contacts 55b, 55c, 55d, and 55e, are provided with dash pot control mechanism as already described. Contacts 55'a and 55', which are operated by relay coil 55', are not dash pot controlled. The purpose of the dash pot is to prevent any one of the chain relays from being energized to effect control until the completion 60 of the time during which all possible signal impulses have entered the chain relay group. Accordingly, the adjustment of the dash pot is such that contacts 55b do not close until the arm 65 21 at station A has contacted the segment spot 20m. The adjusting circuits will be explained later.

70 The next impulse which enters the chain relay group causes the energization of relay coil R2 by the following circuit: from line 46, relay contacts 52a, relay contacts 51a in the position shown, relay contacts R1b in a transferred position, relay contacts R2a, relay coil R2 in the position shown, to line 47. Relay coil R2, upon being 75 energized, shifts its a, b, c and d contacts. The

shifting of the R2d contacts, which are of "make before break" type previously described, transfers the holding circuit for relay R1 back through contacts 52a. Therefore, upon opening of these contacts, relay R1 is deenergized. Relay R2 is held energized through contacts R2a and R3d. In a similar manner each successive impulse entering the chain causes an energization of a new relay and deenergization of the previous one. When the five impulses representative of a card feed 10 are all received, relay R5 is energized to manifest this fact. Shortly thereafter relay contacts 55b close and a circuit is completed as follows: from line 46, relay contacts 55b, switch 56 now closed, contacts R1c, R2c, R3c, and R4c in the position 15 shown, contacts R5c now in a shifted position, solenoid 67, to line 47. This circuit energizes solenoid 67 causing it to pull down its plunger 67a and to close its contacts 67b. The closing of contacts 67b completes a circuit to energize relay 20 coil 68 as follows: from line 46, relay coil 68, contacts 67b, to line 47. The depression of plunger 67a also closes contacts 67c causing relay coil 53 to become energized by a circuit from line 47, contacts 67c, relay coil 53, to line 46. Relay coil 25 53, upon energization, opens its contacts 53a to deenergize relay R5, and also opens its contacts 53b to deenergize relay coil 55. With the energization of relay coil 68, contacts 68a close to complete a circuit from line 46, through contacts 68a, 30 through the punch clutch magnet 70 and back to the right-hand side of line 47. Energization of punch clutch magnet 70 shifts contacts 69 to energize the punch motor 65 by completing a circuit thereto from the left-hand side of line 46, 35 through contacts 69, through motor 65, and back to line 47. The punch motor 65 then operates to effect the feeding of a new record card to the punching position.

40 Station B is now ready to receive the impulses representative of statistical data from station A. One of the digit keys at station A, for example, key 12 (Fig. 1), is now depressed and closes its associated contacts 12b in a previously described manner to effect the energization of the relay coil 45 32. The closure of contacts 32b then completes a circuit from line 26, through contacts 32b now closed through typewriter solenoid S2 and back to the right-hand side of line 304. Energization of solenoid S2 causes printing of the numeral 2 at 50 station A. Closure of contacts 32a causes a pick-up of relay 30 and also relay 38 as previously described so as to prepare the transmitting circuit. Closure of contacts 32c and 32d then permits transmission of two impulses from station A to 55 station B, the transmission of these impulses being effected in the same way as for the card feed impulses.

At station B, upon reception of the two impulses, relay coil R2 becomes energized and, at 60 the time dash pot contacts 55b close, a circuit is completed from the left-hand side of the line 46, through contacts 55b, receiving switch 56 now closed, through contacts R1c in position shown, 65 through contacts R2c in a transferred position, through solenoid 62, to line 47. Plunger 62a is pulled down to effect printing, on the sheet and platen 57, of the numeral 2. Contacts 62c now close to energize relay coil 53 in a previously 70 described manner. Contacts 62b, in closing, energize relay coil 72 by completing a circuit as follows: from line 46, escapement contacts 58, interposer solenoid 72, contacts 62b, to line 47. Interposer solenoid 72, upon being energized, closes 75

interposer contacts 74 to energize the punch magnet 75 by a circuit from the line 46, latch contacts 69 in the position shown, punch magnet 75, * interposer contacts 74, to line 47. In the well-known manner the energization of punch magnet 75 causes the punching of the digit 2 in the record card.

The punching impulse is effected in the first column of the card in the punching position. A skip bar may or may not be used as desired. If no skip bar is used the card is spaced column by column to a first punching position in a manner which is explained later. Energization of the punch magnet 75 causes the depression of the usual punch motor bar on a punch which punches the record card and permits it to move forward one column ready to receive a new perforation. The record card is punched accordingly column by column out to the last data-receiving column. It is then shipped to the actual last column position where it remains because the ejection operation, normally following the moving of the card in the last column position, is rendered ineffective at this time as will be explained later.

The next step in the sequence of events is to cause a re-feeding of the just-punched card into the punch in order that the perforations thereon may be analyzed for verification purposes. This is accomplished by the depression of the so-called verify key 16 at station A (Fig. 1) to send out a series of six impulses to effect the energization of relay R6 at station B (Fig. 2) in the same manner as already described for the transmission of character impulses. As a result of relay R6 being energized, when contacts 55b close a circuit is completed to energize solenoid 102. Contacts 102b then close to pick up coils 103 and 89. Coil 103 is held energized through its 103a contacts and the eject contacts 81, but coil 89 is energized only momentarily to close contacts 89a and energize the card feed knife control magnet 11 which is then held through its 11a contacts, which are closed by lever 18, and rack contacts 64 in the normal position. The card feed knife is deflected downwardly in a manner already described to prevent the feeding of a new card at this time. When the armature lever 18 has depressed the card feed knife sufficiently to lower it below the plane of the card which it would ordinarily feed, contacts 80 are also closed to provide a circuit to energize the punch clutch magnet 10. The energization of the clutch magnet 10 causes the shifting of contacts 69 to energize the punch motor 65. When the punch motor operates, it moves the feed racks up toward the punching position. The card which has just been punched but not ejected is thereby carried back into the punch by one rack, and, the card feed knife having been deflected down, the other rack fails to feed in the usual fresh card. Near the end of the feed stroke, rack contacts 64 are shifted to break the holding circuit to magnet 11. At that time punch clutch contacts 69 are tripped back to normal to deenergize the punch motor 65. The just-punched card has now been fed back into the punch so that the first column is aligned in the punching position.

It is now necessary to condition circuits for analyzing the perforations in the card, column by column. A circuit must first be completed to the contact roll 23 (Fig. 2a) in the following manner. Relay coil 59 (Fig. 2) becomes energized at the end of the feed stroke described above through the shifted rack contacts 64 and

contacts 103c now closed. The holding circuit for coil 59 is from line 47, coil 59, contacts 59a now closed, last column contacts 16 now closed, to line 46. Relay contacts 59b (Fig. 2a) close to provide a circuit to the roll 23. A portion of 5 the card is insulating the roll 23 from the analyzing contact balls 22 at this time, so that no current passes through the roll 23.

As the analyzing station is located one column away from the punching station, it is necessary to provide an automatic spacing of one column so that the re-fed card is moved into a position where its first column is at the analyzing station. To accomplish this, a circuit is completed when commutator arm 25 engages segment spot 24h as follows: from line 46, contacts 103b now closed, escapement contacts 58', commutator arm 25, segment 24h, relay coil 85, contacts 59e now closed, contacts 88c, relay coil 86, to line 47. Contacts 85a (Fig. 2) close upon 10 energization of coil 85 to energize the punch space control magnet 100 by a circuit from line 47, conductor 115, contacts 85a now closed, punch space control relay 100, to line 46. When relay 100 becomes energized, contacts 100b close 15 to energize the punch magnet 75 to allow the card rack to escape one column. The first column of the card is then in position to be analyzed. The position of the perforation in this column determines which one of the analyzing 20 relays 81 to 84 are energized. Assuming a "2" hole is being analyzed, relay 82 will become energized by a circuit from line 47, contacts 59b now closed, contact roll 23, through the hole in the card, relay coil 82, to line 46. 25

Coil 86, which was energized as described previously, is held through its 86a contacts and CC-9. Then, when contacts CC-10 close, a circuit is completed from line 46, conductor 90, contacts 86b, relay coil 88, to line 47. The holding circuit for coil 88 passes through contacts 88a, now closed, and the eject contacts 116. Contacts 88c open to prevent further energization of coil 88 after cam contacts CC-9 open. Also, with contacts 88b now closed, a circuit is completed when the commutator arm 25 engages segment spot 24g as follows: from line 46, contacts 103b now closed, escapement contacts 58' in the normal position, arm 25, segment 24g, contacts 120b also in the normal position, contacts 88b now closed, contacts 59a now closed, relay coil 108, to line 47. Relay coil 108, upon becoming energized, is held in its operated condition through contacts 108a now closed and CC-7.

The circuit for retransmitting impulses to station A is now provided in the following manner: from line 46, contacts 103b now closed, contacts 58' in the normal position, arm 25, segment spot a and then segment spot b, contacts 81b and then contacts 82b, contacts 108c now closed, relay coil 124, contacts 120c in the normal position, resistance 112, to line 47. The potential drop across resistance 112 provides bias to transmitter B for sending impulses to station A for effecting a comparison of the character represented by the retransmitted impulses with the original character recording at station A. With a "2" hole in the card at station B, an impulse is sent out when arm 25 engages segment 20a and again when this arm engages segment 20b.

At the first sending of impulses in the manner just described, relay coil 124 is energized and contacts 124a open to deenergize the relay 81 which was energized upon the shift of the es-

capement contacts during the feed of the card to the first analyzing position. As arm 25 rotates further and arrives at segment spot 24f, it provides a circuit through relay contacts 108e now closed, contacts 87c, and relay coil 89, to line 47. Contacts 89a (Fig. 2) close to energize the punch space control magnet 100 to cause the record card in the punch to be spaced for analysis of the next column. Relay coil 108 (Fig. 2a) becomes energized once again in the manner previously described and a new series of impulses representing the perforation in the newly analyzed column is transmitted back to station A.

15 When a blank column of the card is presented at the analyzing station, a spacing signal comprising a series of four impulses is initiated as will now be explained. After relay coils 87 and 108 are energized in the previously described manner, the commutator arm 25, in passing over segment spots 24a to d, fails to complete a circuit to energize the relay coil 124 because none of the analyzing relay contacts 81b to 84b are closed at this time. The fact that coil 124 remains deenergized, contacts 124a remain closed to maintain relay coil 87 energized. Thus, when the commutator arm engages segment spot 24ee, a circuit may be completed through contacts 108d and 87b now closed, through relay coil 122, to line 47. Contacts 122b now close to energize relay coil 84 which in turn cause relay coils 83, 82 and 81 to also become energized by parallel circuits created by the closing of contacts 84a, 83a, and 82a in succession. Accordingly, with contacts 81b to 84b now also closed, four impulses are successively transmitted by the next passage of the commutator arm 25 over the segments 24a to d. Reception of the four impulses at station A is indicative of the blank space in the column of the card at station B which was just analyzed.

Upon the completion of transmission of the character impulses and space impulses for all columns of the card back to station A, the ejection of the card occurs following the operation of the last column contacts 76 and 110. Contacts 76 open to deenergize relay coil 59. The pickup circuit to a coil 126 is thus broken by the opening of contacts 59g, although the holding circuit for that coil remains intact through contacts 126a now closed and eject contacts 115, the coil 126 having been energized at the time the energization of relay coil 59 caused the closing of contacts 59g. With relay coil 126 still energized its contacts 126b remain closed, and when last column contacts 110 close, a circuit is completed to energize the stacker magnet 105 to eject the card. The energization of the stacker magnet opens eject contacts 115 to deenergize relay coil 126. Eject contacts 97 (Fig. 2) are also operated at this time to deenergize the verifying control magnet 108.

Reception of the verification impulses at station A effects the pickup of the corresponding relays R1 through R4 (Fig. 1a), depending upon the signal impulses transmitted. In a manner similar to that described for station B, energization of these relays and subsequent closure of relay contacts 55b effects printing of the proper character at station A. The reception of four impulses energizes the space magnet 130 to effect a spacing operation. The relay 53 at station A is energized after printing occurs and relay contacts 53a effect the reset of the chain relay system as previously described. The operator at station A now compares the printed data which

was originally transmitted with the printed data which has just been received. If this data verifies, the operator depresses the card feed key 15 (Fig. 1) and printing and punching for a new record are effected. If the card fails to verify, the adjust key 17 is depressed and causes a pick-up of a green or red signal at station B. The signal circuits will be explained later. Such a signal at this time indicates to the B operator that the card failed to verify and accordingly the just punched card is removed. Adjustment is then made in a manner to be described presently. A new series of operations then ensues for the same data and if this also fails to verify, it is understood that the machine is in need of repair. 15

In starting up and at various times it is necessary to adjust the dash-pot controls at both of the stations to insure proper timing of certain circuits associated with the receiving chain of relays. The present transmission system requires one or more of a series of impulses to effect transmission of statistical data as already described. Each impulse of this series energizes a corresponding relay and causes deenergization of the one just preceding it. Because of this the last relay energized is representative of the transmitted signal, and no relay must become effective until the time for picking up the last relay in the group has been passed. This timing is effected by dash-pot controlled relay contacts, the adjustment for which will now be described.

These contacts at station B which are dash-pot controlled must close within a period determined by the speed of rotation of the transmitting commutator at station A. That is, the first of a series of impulses triggers off the dash-pot relay 55. The contacts controlled by this relay must not function before the time has passed when the last possible transmitting signal impulse might be received from station A. 40

Therefore, since the first impulse from station A triggers off the dash-pot relay at B, if the time of closure of these points is checked by an additional impulse following the time of signal impulses, it is possible to determine if the adjustment is correct or not on the dash-pot relay. Means is provided to automatically effect correct adjustment at station B by the signal of adjustment from station A and likewise station B to A. For the machine to be in adjustment, the contacts 55b must close following the completion of the signal impulses and while the arm 21 at station A is contacting segment spot 20m. 45

When starting up sending operations, for example, each morning prior to beginning transmission, the operator at station A begins the adjusting operations. Operator at station A depresses the adjusting key 17 and operator at B opens receiving switch 56 prior to adjusting to prevent printing. Depression of key 17 effects the transmission of seven impulses to station B and energization of relay R7 at this station in the customary manner. Sets of contacts 55c, 55d, and 55e are operated concurrently with contacts 55b for testing the adjustment, and contacts 55f concurrently with 55'a. The segment spot 20m which is used for adjusting purposes is longer than any of the other segment spots. This is to hold relay R7 energized for an appreciable period and allow some tolerance in the adjustment of the dash-pot relay. Relay R7 is not provided with the usual holding circuit through contacts at station B. Hence, relay R7 is energized only while the arm 21 contacts segment 20m. If contacts 55c close while relay R7 55

is energized, the dash-pot control (Fig. 2) is in adjustment, and a circuit is completed as follows: line 46, relay contacts 55c now closed, relay contacts R1e now closed, contacts 131c, coil 133, to line 47. Relay 133 upon energization is held energized through its points 133a and relay contacts 51d and 120r. Relay contacts 133a, in closing, light a green lamp in the holding circuit which informs the operator at station B that his machine is in adjustment. Also, relay 63 is energized to open its 63a contacts and drop relay 55. Operator at B would then begin sending an adjusting impulse to station A to operate similar circuits at the latter station in a manner to be described shortly.

If the dash-pot control at station B is too rapid, the sequence of events is as follows: The contacts 55e become closed before the adjusting impulse opens contacts R1g and relay coil 131 is energized by a circuit from line 46, contacts 55e, contacts R1g, relay coil 131, to line 47. Relay coil 131 is held energized through contacts 131a and contacts 51d and 120r. Contacts 131b close to energize relay coil 132 when R1h closes, coil 132 being then held through contacts 132a, 51d and 120r. Relay contacts 132a, in closing, light a red lamp in the holding circuit to show that the adjustment is not correct.

If the dash-pot control at station B is too slow, contacts R1f open and close before contacts 55d open and thus relay coil 134 is energized. Also, coil 131 is energized, but coil 132 is not energized at this time. A red light in the holding circuit indicates machine is still out of adjustment. The energization of coil 134 automatically effects an adjustment of the dash-pot mechanism to speed up the relay action by closing points 134b and energizing the adjusting magnet 135 (Fig. 2a) which causes shaft 6 (Fig. 6a) to rotate counterclockwise to effect a speeding up of the dash-pot action by increasing the size of the opening 7 as has been previously explained. Closure of 132b points energizes magnet 136 to slow up the dash-pot action by causing a clockwise rotation of shaft 6.

To transmit an adjusting impulse from B to A the adjust key 104 is depressed to energize relay coil 120 (Fig. 2). Relay 120 is then held through its contacts 120a and normally closed contacts 138d in parallel with CC-6. The 120e contacts (Fig. 2a), in closing, cooperate with the shifting of contacts 120b to provide a circuit for picking up relay coil 138 when arm 25 contacts spot 24g. The 138b contacts then close to provide for transmitting the adjusting impulses through the contacts 120f, g, h, k, m, and the transferred contacts 120c. An impulse circuit may be traced as follows: from line 47, resistance 112, contacts 120c in a shifted position, contacts 138b now closed, contacts 120f, 120g or 120h, etc. now closed, corresponding commutator segment 24a, 24b, or 24c, etc., arm 25, contacts 120e to line 46. The last impulse occurs when arm 25 is on segment 24e and effects adjustment at A in a manner similar to that already described for station B.

The operator at A seeing his adjusting lights flashing knows station B is in adjustment, and that he may discontinue transmission of his adjusting signal to station B. Station A being in adjustment, the operator there sends back a single adjusting impulse to station B which indicates this fact to the B operator. The relays 131-134 are deenergized either upon the next 75 incoming signal, at which time relay coil 51 is

energized and opens its 51d points, or when contacts 120r open upon sending an adjusting signal. Relay coil 120 (Fig. 2) is held energized through contacts 138d and CC-6 in parallel. Contacts CC-6 close before coil 138 is energized to open its contacts 138d, but contacts CC-6 open before contacts 138d reclose upon deenergization of 138, and relay 120 is dropped at this time.

Relay coil 55 becomes deenergized when the solenoids 135 or 136 shift their associated ratchet arms 91 and 92 so as to open contacts 60 or 61. When the adjustment is correct, pick-up of relay coil 63 (Fig. 2) opens 63a (Fig. 2a) to drop coil 55. While coil 63 is energized, the holding circuit of coil 55 is open, and it is necessary therefore that coil 51, when energized, remains in its operated condition long enough to drop coil 63. Coil 51 is then deenergized in a previously described manner and its contacts 51c close to pick up coil 55 once again.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. A data recording system comprising a first station having therein a primary recording means to record original data, a primary data transmitting means, and a data verifying means; in combination with a second station having duplicating means controlled by the transmitted data for duplicating the data on a multi-column record, one column of data being duplicated in a corresponding column of the record upon each operation of the duplicating means, spacing means controlled by and operated as an incident to the duplicating means upon each operation thereof to space the record so as to bring the next data-receiving column of the record into alignment with the duplicating means, record analyzing means for analyzing the columns of the record successively for duplicate data thereon, and a secondary transmitting means controlled by the analyzing means upon analysis of each data column for operating the data verifying means directly in accordance with the analyzed duplicate data to provide a comparison between the latter data and the original data at the first station.

2. A data recording system comprising a first station having therein a primary recording means to record original data, a primary data transmitting means, and a data verifying means; in combination with a second station having perforating means controlled by the transmitted data for perforating the data in a multi-column record, one column of data being perforated in a corresponding column of the record upon each operation of the perforating means, spacing means controlled by and operated as an incident to the perforating means upon each operation thereof to space the record so as to bring the next data-receiving column of the record into alignment with the perforating means, record analyzing means for analyzing the columns of the record successively for data perforations therein, and a secondary transmitting means controlled by the analyzing means upon analysis

of each data column for operating the data verifying means directly in accordance with the analyzed data perforations on the record to provide a comparison of the latter data with the original data at the first station.

3. A data recording system comprising a first station having therein a primary recording means to record original data, a primary data transmitting means, and a data verifying means; 10 in combination with a second station having duplicating means controlled by the transmitted data for duplicating the data on a multi-column record, one column of data being duplicated in a corresponding column of the record upon 15 each operation of the duplicating means, spacing means controlled by and operated as an incident to the duplicating means upon each operation thereof to space the record so as to bring the next data-receiving column of the record 20 into alignment with the duplicating means, record analyzing means, record feeding means effective upon analysis of the last column of data in the corresponding column of the record for feeding the record into a predetermined position 25 to bring the first of the columns of the record to receive the data into operating alignment with the analyzing means, means controlled by the analyzing means for operating the spacing means to present in succession to the analyzing 30 means the columns of duplicate data on the record, and a secondary transmitting means also controlled by the analyzing means upon analysis of each column of the record for transmitting the analyzed duplicate back to the first station to 35 operate the data verifying means accordingly to compare the latter data with the original data at the first station.

4. A data recording system comprising a first station having therein a primary recording means 40 to record original data, a primary data transmitting means, and a data checking means; in combination with a second station having perforating means controlled by the transmitted data for perforating the data in a multi-column record, one column of data being perforated in a corresponding column of the record upon each operation of the perforating means, spacing means controlled by and operated as an incident to the perforating means upon each operation thereof 45 to space the record so as to bring the next data receiving column of the record into alignment with the perforating means, record sensing means, record feeding means effective upon the sensing of the last column of the record for feeding the record into a predetermined position to bring the first of the columns of the record into operating alignment with the sensing means, means controlled by the sensing means for operating the spacing means to present in succession to the sensing means the columns of the record 50 having data perforations, and a secondary transmitting means also controlled by the sensing means upon the sensing of each of said columns of the record for transmitting the sensed data from the record back to the first station to 55 operate the data checking means.

5. A data recording system comprising a transmitting station having therein a primary recording means to record original data, a primary 70 means to transmit primary impulses representing said original data, and data comparing means; in combination with a receiving station embracing therein receiving means including a plurality of serially arranged relays adapted to 75 be energized in succession by and in accordance

with the transmitted impulses, perforating means controlled by the last energized relay in the series to perforate the data on a multi-column record, a column of data being perforated in a corresponding column of the record upon each 5 operation of the perforating means, record analyzing means for analyzing the columns of the record successively for data perforations therein, and a secondary transmitting means controlled directly by analyzing means upon analysis 10 of each data perforation in the record for transmitting secondary impulses representing said data perforation to the data comparing means to effect a comparison between the data represented by the latter impulses and the corresponding 15 original data at the transmitting station.

6. In combination, a transmitting station including therein means to transmit primary impulses representing original data during a predetermined time interval, a primary recording means operated as an incident to and in accordance with the operation of the transmitting means to record the original data, and data comparing means; and a receiving station embracing therein means for receiving said impulses, perforating devices controlled selectively by the receiving means in accordance with the transmitted impulses for perforating a multi-column record, time delay means for rendering the receiving means ineffective to operate the recording means 30 until after a time delay corresponding to the predetermined time interval, analyzing means operable after a predetermined number of columns of the record have been perforated for analyzing said columns successively for perforations therein, and means controlled by the analyzing means directly upon analysis of each perforation in the record for operating the data comparing means to effect a comparison between the data perforated in the record and the corresponding 35 original data at the transmitting station.

7. In combination, a transmitting station including therein transmitting means for transmitting primary impulses representing original data, a primary recording means operated by and as an incident to the operation of the transmitting means for recording said original data, and data matching means; and a receiving station remote from the transmitting station comprising receiving means responsive to the transmitted impulses, 45 perforating means controlled by the receiving means for making data-representing perforations in predetermined portions of a record card, means operable following the reception and perforation of the data for analyzing said portions 50 of the record successively for said perforations, and a secondary transmitting means controlled solely by the analyzing means and rendered effective upon analysis of each of the portions of the record for sending secondary impulses representing the perforated data therein to the transmitting station to operate the data matching means to compare the perforated data represented by the secondary impulses with the original 55 data at the transmitting station.

8. In combination, a transmitting station including therein transmitting means for transmitting primary impulses representing original data characters, a primary recording means operated by and as an incident to the operation of the 70 transmitting means for recording said data characters, and data matching means; and a receiving station remote from the transmitting station comprising receiving means responsive to the transmitted impulses, perforating means con- 75

trolled by the receiving means for perforating the data characters in a record card, card feeding means to feed said record to the perforating means, and means normally operating said record feeding means at a time following the occurrence of a predetermined number of perforating operations to feed a fresh card to the perforating means, means to suppress the card feeding means at this time and concurrently to cause the re-feeding of the perforated card, analyzing means adjacent the perforating means for analyzing the

perforations in the latter card successively, and a secondary transmitting means controlled by the analyzing means upon each analysis of a data perforation to transmit secondary impulses representing the corresponding data character back 5 to the transmitting station to operate the data matching means accordingly to compare the data characters from the card represented by the secondary impulses with the corresponding original data characters. 10

JAMES W. BRYCE.
